UNITED STATES PATENT OFFICE

ANTHONY IORIO, OF CORONA, NEW YORK

DESIGN FOR AN INCENSE BURNER

Application filed March 10, 1931. Serial No. 39,021. Term of patent 14 years.

To all whom it may concern:

Be it known that I, ANTHONY IORIO, a citizen of the United States, residing at Corona, in the county of Queens and State of New York, have invented a new, original, and ornamental Design for an Incense Burner, of which the following is a specification, reference being had to the accompanying drawing, forming part thereof.

The figure is a perspective view, showing my new design.

The appearance of the incense burner is the same on both sides thereof.

I claim:

The ornamental design for an incense burner, as shown and described.

ANTHONY IORIO.
